UNITED STATES PATENT OFFICE.

GOTTLOB HONOLD, OF STUTTGART, GERMANY, ASSIGNOR TO THE FIRM OF ROBERT BOSCH, OF STUTTGART, GERMANY.

APPARATUS FOR ELECTRIC IGNITION.

1,085,340.

Specification of Letters Patent.

Patented Jan. 27, 1914.

Application filed March 29, 1911. Serial No. 617,553.

To all whom it may concern:

Be it known that I, GOTTLÖB HONOLD, engineer, a subject of the German Emperor, residing at 11-13 Hoppenlastrasse, Stuttgart, Germany, have invented certain new and useful Improvements in Apparatus for Electric Ignition; and I do hereby declare the following to be a full, clear, and exact description of the invention, such as will enable others skilled in the art to which it applies to make and use the same.

The present invention relates to apparatus for electric ignition of the combustible gases in a single or multiple cylinder internal combustion engine.

As is well understood by those conversant with the art, the full development of pressure produced in the cylinders of engines of this kind by the explosion of the fuel should always take place immediately after the crank has passed the dead point at the head end of the stroke. Now under ordinary conditions the time which elapses between the moment in which the igniting spark is generated and the moment in which the exploding combustible mixture develops the maximum pressure, is more or less constant, and it follows that, if the maximum pressure is to be developed in a certain phase of the stroke, the moment of ignition or of generating the spark must be advanced when the speed of the engine is increased. Hitherto therefore in engines of this kind means have invariably been provided for shifting the apparatus controlling the moment of ignition, that is to say the interrupter of the primary current. This method of mechanically adjusting the igniting apparatus involves the necessity of making this apparatus accessible to the operator either directly or by providing transmitting means such as rods, levers, chains and such like.

It is the object of my invention to obviate the use of such mechanical transmitting members and substituting therefor electric means which are much more easily adapted to all such dispositions of machinery in which the operator controlling the engine cannot be given direct access to all parts of the machinery under his control during operation, such as is the case for instance in the operation of motor cars, motor boats and the like.

According to my invention, in order to obviate the necessity of making the spark 55 point or the point of interruption of the primary current adjustable, I propose to take advantage of the fact that the time consumed between the moment of ignition and the moment in which the full pressure of the explosion is developed, can be made to vary considerably by varying the number of sparks employed to ignite the explosion mixture. I have found by experiment that, if, instead of employing only one spark to ignite the explosive mixture in the cylinder, I employ a plurality of simultaneous sparks, the time consumed by the process of explosion or in other words the time elapsing between the moment of ignition and the moment in which the maximum pressure is developed is considerably reduced. Moreover I have found that as the number of simultaneous igniting sparks is increased 75 the time absorbed by the process of explosion does not only diminish in inverse proportion to the number of sparks, but according to a higher power. The exact law by which the diminution of the time of explosion is governed is not readily capable of a general expression, because it is subject to great variations depending upon the size and dimensions of the cylinder, the degree of compression and other similar conditions, that may vary considerably. In any case however the increase of speed of combustion with duplicate sparking plugs only is so great that I find it possible, even for the highest practical speeds of the engine 80 crank, to fix the moment of ignition so as to make it coincide with the dead point of the crank at the head end of the stroke or only very slightly in advance of the dead point. If then, by means hereinafter more 85 fully described, one of the pair of sparking plugs is made inoperative, the engine will thus be adapted to be run at slow speeds or to be started without the risk of sudden reverses occurring.

My invention therefore consists in providing an internal combustion engine with a plurality of sparking plugs for every cylinder and instead of employing the usual mechanical means for shifting the moment 105 of ignition or of interruption of the primary igniting current according to the speed of the engine, I provide means for switching

on or off one or more sparking plugs in every cylinder accordingly as the engine is to be adapted to higher or lower speeds.

In practice and more especially with smaller sizes of engines I find it sufficient to provide two sets of sparking plugs connected to the generating plant in such a manner that both plugs of each cylinder will generate their sparks simultaneously. In the accompanying drawings therefore I have illustrated an embodiment of my invention in which the number of sets of sparking plugs is thus limited, because comprehension of the nature of my invention is thus rendered more easy. But I wish it to be understood that I do not limit myself to double sets of plugs. In unusually large engines or in cases in which unusual variations of speed are required, it may become necessary or desirable to use a larger number of sets of plugs. But the manner in which they are to be employed according to my invention will be substantially the same in all cases and any expert will be readily able according to rules well known and understood in the art to so modify and multiply the connections shown in the drawing as to adapt the arrangement to the use of multiple sets of sparking plugs.

In the accompanying drawings Figure 1 is a diagrammatical illustration of the means employed for reducing my invention to practice by means of a magneto igniter and of the manner in which such means are to be connected in order to act according to my invention. Fig. 2 is a diagrammatical illustration of a modification of the means shown in Fig. 1 and Fig. 3 is a diagrammatic illustration of a modification of the connections shown in Figs. 1 and 2, as employed in case 40 in which the igniting sparks are to be generated by means of a battery instead of a magneto.

Corresponding parts are designated by the same reference characters in all the drawings.

Referring to Fig. 1 C represents the head end of a cylinder of an internal combustion engine the inner end being drawn broken away and P the piston thereof.

K₁ and K₂ are a pair of sparking plugs of usual construction having one electrode connected to a clamping screw at the head of the plug and the other electrode connected to the mass of the cylinder or to ground.

A is a magneto-generator of usual construction supposed to be driven by the engine or in any other suitable and usual manner.

S₁ and S₂ are a pair of sliprings preferably mounted on the armature shaft of the magneto and rotating therewith and being connected to the terminals of the secondary armature winding by means of insulated wires E₁ and E₂.

B₁ and B₂ are a pair of brushes adapted to slide on said sliprings S₁ and S₂ and con-

nected by leads L₁ and L₂ to the clamping screws of the sparking plugs K₁ and K₂.

D is the contact lever of a switch connected by a lead L₃ to the mass of the cylinder and being capable of making connection alternately with contacts D₁ and D₂ connected by leads L₄ and L₅ to points on leads L₁ and L₂ intermediate the brushes B₁ and B₂ and the plugs K₁ and K₂.

The primary winding P, of the magneto armature includes a mechanical interrupter, which is operated according to rules well known in the art either from the armature shaft or any other suitable moving part of the engine so as periodically to short circuit and to interrupt the primary winding and according to my present invention this interrupter may have a fixed adjustment, so as to cause an interruption every time the piston arrives at the dead point at the head end of the stroke or very shortly before that point. Likewise it will be understood that, in order to accommodate a plurality of cylinders instead of a single one, as shown in the drawing, a distributor will have to be added which, according to methods well understood, may be placed either in the circuit of the primary or that of the secondary current.

The arrangement thus illustrated operates as follows: Every time a current impulse is generated by the armature of the magneto it is transmitted through the sliprings S₁ and S₂, the brushes B₁ and B₂, the leads L₁ and L₂ to the plugs K₁ and K₂. When the switch D is in the central position, as shown in the drawing, both plugs are connected in series and simultaneous sparks are generated in both, thus adapting the engine to high speeds. When low speeds are required or when the engine has been at rest and it is intended to start it, the switch lever D is turned to make contact either with D₁ or D₂. In the first instance the plug D₁ and in the second instance the plug D₂ is short circuited and the current impulse therefore generates a single spark in the remaining plug. The time elapsing between the moment of ignition and the development of the full pressure of the explosive is thus increased and the lag thus obtained is sufficient to obviate reverses of the engine in starting and to produce a good output when the engine is kept at low speeds for a longer period of time.

In Fig. 2 a modification of this arrangement is shown which differs from that illustrated in Fig. 1 only in the arrangement of the brushes and sliprings, these parts being disposed in such a manner as to obviate the necessity of placing both sliprings in different planes, thus diminishing the length of armature shaft required to accommodate the sliprings. Instead of providing two separate sliprings, in this case I divide one slipring into two segments S₁ and S₂ arranged

in the same plane and connect the terminals of the secondary armature winding A_1 with these segments exactly in the same manner as described with reference to the separate sliprings in Fig. 1. This arrangement has the effect that the direction of every second current impulse passing through the plugs is reversed. But, since the direction of the current which is employed for generating an igniting spark is of no importance, this difference does not produce any change in the operation of the arrangement.

Fig. 3 illustrates the connections used for embodying my invention in such cases in which a battery is preferred for generating the sparking current. One terminal of a battery B is grounded at B_1 and is thus in connection with the mass of an interrupter I , the latter connection being made separable by means of a switch s that is drawn opened but is supposed to be closed during operation. On a lever 1 fulcrumed at 2 on the frame of the interrupter is disposed a movable contact pin 3 and on a block 4 secured to the frame of the interrupter but insulated therefrom is disposed another contactpin 5. A spring 6 secured at one end to a block fastened on or integral with the frame plate of the interrupter and secured at the other end to the tail end of lever 1 tends to retain the pins 3 and 5 in contact with each other. Block 4 is connected to one terminal of a primary winding G_1 of an induction coil G the other terminal being connected to the second terminal of the battery.

The frame plate of the interrupter is supposed to be mounted on a rotating part of the engine so as to take part in the rotation in accordance with the well understood practice of the art and a cam 8 deflects the tail end of lever 1 at determined periods and thereby separates the contact pins and interrupts the circuit.

Coil G is provided with a secondary winding G_2 one terminal of which is connected to the rotating contact or brush of a distributor F_1 and the other with the corresponding brush of a distributor F_2 . Four cylinders C_1, C_2, C_3 and C_4 are shown, the head plates only being drawn and each cylinder is provided with two sparking plugs, cylinder C_1 having the plugs K_1' and K_2' , the cylinder C_2 the plugs K_1'' and K_2'' and so forth and the insulated electrodes of the plugs are connected in the respective order with stationary contacts $f_1', f_1'', f_1''',$ and so forth of distributors F_1 and F_2 . The terminals of the secondary winding G_2 are bridged by a switch D with contacts D_1 and D_2 arranged as in the modifications described with reference to Figs. 1 and 2.

The brushes of the two distributers are supposed to be coupled in such a manner that they connect corresponding plugs with the secondary winding in the order required for

firing the four cylinders according to known methods of operation in multicylinder engines.

In the position of all parts shown, when the battery current is interrupted at 3, 5, a current impulse is induced in the secondary winding G_2 and is conducted by means of the distributers F_1 and F_2 to the sparking plugs K_1' and K_2' and the spark of these two plugs being disposed in series two simultaneous sparks are produced thus enabling the engine to run at high speed and produce its full output.

When the switch lever D is moved into contact either with D_1 or D_2 either the set of sparking plugs indexed "1" or the set indexed "2" is shortcircuited and the other set only remains in operation thereby increasing the time elapsing between the moment of interruption and the moment in which the maximum pressure is developed by the explosive and enabling the engine to develop full power at low speeds or making it capable of being started without danger of reverses.

It stands to reason that the action of the arrangement illustrated in Fig. 3 would be substantially the same if for the battery a magneto-generator was substituted for generating the sparking current and also that a number of other modifications of the connections herein illustrated by way of example might be elaborated for producing the same effect. But I wish it to be understood that my invention is not concerned with these details which are all well known and understood, but that it refers only to the described method of and means for varying the time consumed in the process of explosion for the purpose of obviating the use of means for shifting the moment of ignition or the moment of interruption of the primary current.

What I claim is:

1. In an electric ignition system for an internal combustion engine, a plurality of spark plugs in a cylinder of the engine, a source of sparking voltage including a single secondary winding, means for generating in said secondary winding at all speeds of the engine a sparking voltage in fixed time relation to the successive periods of maximum compression in the cylinder, electrical connections for connecting the secondary winding to all the spark plugs simultaneously thereat, and a switch and connections for rendering permanently inoperative one of said spark plugs at will without rendering other or others of the spark plugs inoperative.

2. In an electric ignition system for an internal combustion engine, two spark plugs in a cylinder of the engine, a source of sparking voltage including a single secondary winding, means for generating in said

- secondary winding at all speeds of the engine a sparking voltage in fixed time relation to the successive periods of maximum compression in the cylinder, electrical connections for connecting the secondary winding to all the spark plugs to produce sparks simultaneously thereat, a multi-point switch and connections for rendering both spark plugs operative, for short-circuiting at will one of the spark plugs to render it permanently inoperative, and for short-circuiting at will the other of the spark plugs to render it permanently inoperative.
3. In an electric ignition system for a multiple cylinder internal combustion engine, a plurality of spark plugs in each cylinder, a magneto-generator having a primary and a secondary circuit, means for periodically short-circuiting and interrupting the primary circuit to generate at all speeds a sparking potential in fixed time relation to the successive periods of maximum compression in the several cylinders, electrical connections including a distributor for successively connecting the generator with the spark plugs in the several cylinders to produce sparks thereat substantially at the time when the maximum pressure exists in each cylinder, and a switch and connections for rendering inoperative one or more spark plugs in each of the several cylinders.
4. In an electric ignition system for an internal combustion engine, two spark plugs in the cylinder of the engine, a magneto-generator having primary and secondary windings and a slip ring comprising two insulated segments electrically connected to the terminals of the secondary winding, means for periodically closing and interrupting the circuit of the primary winding in fixed time relation to the period of maximum compression in the engine cylinder, a pair of diametrically disposed brushes adapted to contact with the slip ring, electrical connections for connecting the brushes with the insulated electrodes of the spark plugs, and a switch and connections for rendering inoperative one of the two spark plugs.

In testimony whereof I have affixed my signature, in presence of two witnesses.

GOTTLOB HONOLD.
